UNITED STATES PATENT OFFICE.

ALFRED W. HILLIBISH, OF CANTON, OHIO.

DESIGN FOR A NECKTIE-FASTENER.

SPECIFICATION forming part of Design No. 34,021, dated February 5, 1901.

Application filed January 11, 1901. Serial No. 42,932. Term of patent 7 years.

To all whom it may concern:

Be it known that I, ALFRED W. HILLIBISH, a citizen of the United States, residing at Canton, in the county of Stark and State of Ohio, have invented and produced a new and original Design for Necktie-Fasteners, of which the following is a specification, reference being had to the accompanying drawings, forming part thereof.

Figure 1 is a side view. Fig. 2 is an edge or end view.

As shown in the drawings, the leading or material feature of my design consists of two extended members 1, curved upward from the points 2 and terminating at the points 3. The upper ends of the curved members 1 are bent or curved, forming the loops 4. From the points 2 extend upward the parts 5 to the points 6, at which points the members 5 are curved and extended downward substantially parallel with each other to the points 7, where

said members are curved or inclined at an angle and continued to the curved points 8, from which points the members 9 extend upward and their upper ends joined by the curved portion 10, thereby forming an open loop below the portion 10, and by extending the members 5 upward from the points 2 and then downward the open space 11 is formed above the portion 10.

Having described my invention, what I claim as new, and desire to secure by Letters Patent, is—

The design for a necktie-fastener as herein shown and described.

In testimony that I claim the above I have hereunto subscribed my name in the presence of two witnesses.

ALFRED W. HILLIBISH.
